US0D1054107S

(12) **United States Design Patent** (10) **Patent No.:** **US D1,054,107 S**
(45) **Date of Patent:** **** Dec. 10, 2024**

(54) **SHIELD**

(71) Applicant: **KNIGHT SHIELD Sàrl**, Bursins (CH)

(72) Inventor: **Enzo Battaglieri**, Presinge (CH)

(73) Assignee: **KNIGHT SHIELD Sàrl**, Bursins (CH)

(**) Term: **15 Years**

(21) Appl. No.: **35/518,076**

(22) Filed: **Feb. 15, 2023**

(80) **Hague Agreement Data**

Int. Filing Date: **Feb. 15, 2023**

Int. Reg. No.: **DM/227228**

Int. Reg. Date: **Feb. 15, 2023**

Int. Reg. Pub. Date: **Aug. 18, 2023**

(51) **LOC (14) Cl.** **29-02**

(52) **U.S. Cl.**

USPC **D29/101.3**
